9 Claims. (Cl. 179—170)

This invention relates to alternating current signalling systems having a plurality of paths through which alternating current signals in rectified or unrectified form may pass, for instance, one or more of the paths may take the form of a main transmission path and/or one or more of the paths may take the form of a control path.

One example of such a system is a two-way telephone transmission system in which the main transmission paths are the "go" and "return" paths; the invention, however, is also applicable for instance to telephone systems in which the main transmission paths are both "go" paths. 15 The principal object of the invention is to ensure that no harmful effects can take place when one transmission path is to be used in place of another.

One of the features of the invention relates 20 to arrangements whereby when a transfer is effected from one transmission path to another the order in which the successive changes are made is predetermined so as to preclude the possibility of interaction taking place, while another 25 feature of the invention relates to arrangements whereby the determination of when one transmission path is to be used in place of another is determined in a more positive manner even with weak currents in the path which is being 30 taken into use.

According therefore to the first feature of the invention attenuation networks connected in one or more paths are jointly controlled by changes in the applied control voltage and each 35 network is given a bias, for instance by a normal biasing current flowing therethrough, so as to ensure that when the applied control is varied other than instantaneously the critical changes in the attenuation of the networks take place 40 in a predetermined order depending upon the relative bias of the respective networks so as to ensure that conditions deleterious to the operation of the system cannot occur.

According to another feature of the invention 45 in addition to controlling the substitution of one transmission path in place of another in accordance with the relative effective strength of the signals in the two paths, a third controlling effect is introduced which is dependent upon the 50 strength of the signals in the path in which through transmission is taking place, which is arranged to effect the relative effective strength of one set of signals in such a way that the changeover is effected in a more positive man-

ner even with weak currents in the path which is being taken into use.

By way of example, in a two-way telephone system in which the "return" transmission path is closed so as to prevent through transmission during transmission in the "go" transmission path, according to the present invention a voice operated device which may also be an amplifier either in the main transmission path or in a control path is provided controlling the closing, i. e., 5 the preventing of through transmission and opening, i. e. the permitting of through transmission, of the "return" path which has a main input to which signals derived from the input side of the "go" path are applied to operate the device to close the "return" path and/or open the "go" path, a reply input to which signals derived from the input side of the "return" path are applied during signal transmission in the "go" path to operate the device in the reverse 10 direction to open the "return" path and thereby enable reply signals to break in, and a third input which in this example might be termed "anti-echo" input to which signals derived from the "go" path are applied to prevent any signals, such as echo signals, created in the "return" path 15 due to signals in the "go" path effecting the reverse operation of the device to open the "return" path.

A further feature of the invention relates to 20 the timing arrangements which enable weak signals in one path to cause transmission in that path to be substituted for transmission in another path with the minimum of delay and this is effected by arranging that the normal change-over or hangover time should just exceed the normal time which elapses between words and syllables while the time during which the effect of echo or like signals derived from signals in the path in which transmission is taking place is only 25 just longer than the time during which echo signals must be received so that weak signals occurring in the path in which through transmission is prevented can be effective after the cessation of echo or like signals and before the cessation of the normal changeover time to hasten the time at which the changeover will take place.

Operation of the said voice operated device is 30 preferably dependent on the voltage across a condenser, a rectifier being arranged to rectify the signals applied to the main input and to apply the rectified signals to the condenser. A further rectifier may be arranged to rectify the 35 signals applied to the reply input and to apply 40 the rectified signals to the condenser. A further rectifier may be arranged to rectify the 45 signals applied to the reply input and to apply 50 the rectified signals to the condenser. A further rectifier may be arranged to rectify the 55 signals applied to the reply input and to apply

the rectified signals to a condenser on the voltage across which the operation of the said voice operated device is dependent. An amplifier would preferably be arranged to amplify the signals applied to the reply input before rectification. In addition a rectifier may be arranged to rectify the signals applied to the third or anti-echo input and to apply the rectified signals in opposition to the signals derived from the reply input whereby rectification of echo signals is made more or less non-effective. The rectified signals from the third or anti-echo input may charge a condenser having a discharge time slightly greater than the time taken for echo signals to pass round a circuit and through the reply input, and appreciably less than the discharge time of the condenser to which rectified main signals are applied. The condenser or condensers may be arranged in the grid circuit of a thermionic valve to control the grid bias of the valve. This valve may also be arranged in one of the transmission paths to amplify the signals therein.

A similar voice operated device may control the opening and closing of the "go" path, the "go" path being closed during transmission in the "return" path. The opening and closing of the transmission path may be effected by varying the attenuation of attenuation networks arranged in the paths and adjusted to prevent instability in either the quiescent or transfer state due to coupling between the paths and the voice operated device, the arrangement being such that operation of a device to close one path results in an increase in the attenuation of that path as well as decrease in the attenuation of the other path. Thus a pair of attenuation networks may be arranged in series in each of the transmission paths, one network of each pair having a low attenuation and the other a high attenuation in the quiescent state and the steady decrease of the attenuation of a path may then be effected by decreasing the attenuation of the network having a high attenuation. Alternatively, both transmission paths may be closed in the quiescent state and the voice operated devices so arranged that operation of either of the devices to open one of the transmission paths effects the closing of the main input to the other voice operated device, whereby the operation of the said other device to close the open transmission path is prevented by echo signals or signals derived from the open transmission path applied to its main input. Thus an attenuation network which has low attenuation in the quiescent state may be arranged in the main input to each voice operated device and the said closing of the main input effected by increasing the attenuation of the network. Each attenuation network preferably comprises one or more dry plate rectifiers arranged in series and/or shunt arms, the attenuation being varied by passing direct current through the rectifier or rectifiers. In the case of a system having two voice operated devices, each including a thermionic valve, the said direct current may be dependent on the difference of the anode currents of the two thermionic valves. Where more than one attenuation circuit is controlled by a single variation of the controlling voltage or controlling current it is possible by giving a normal bias to each network, which is different to all the other networks, to arrange that one network is closed before another is opened so as to ensure that conditions are not created which would result either in the creation of intermittent interruption

or "howling" conditions or other effect deleterious to the operation of the system.

It will be understood that in certain cases no biasing condition might be applied to either one or more of the networks. The absence of a biasing condition would serve to distinguish from networks which have a biasing current or voltage and to enable the order of opening and/or closing of the respective networks to be determined.

The invention will now be described by way of example with reference to the accompanying drawings of which:

Fig. 1 is a schematic diagram of a loudspeaker telephone equipment for attachment to a telephone line.

Fig. 2 shows the circuit represented by Fig. 1 in detail.

Fig. 3 is a schematic diagram showing the application of the invention to a two-wire repeater circuit, while

Fig. 4 is a schematic diagram showing the arrangement by which the different biasing effects are applied to the attenuation networks of Fig. 1.

As shown in Fig. 1, a microphone 1 and a loudspeaker 2 are coupled to a telephone line 3 through a differential transformer or hybrid coil 4 having the usual balance network 5. The path from the microphone 1 to the transformer 4 extends through a first stage amplifier 6, a second stage amplifier 7 and a normally closed attenuation network 8. The path from the transformer 4 to the loudspeaker 2 extends through a volume control device 9, a first stage amplifier 10, a normally closed attenuation network 11 and a second stage amplifier 12. In the arrangement shown in Fig. 1, the second stage amplifier 7 and the first stage amplifier 10 in addition to serving as amplifiers in the main signal paths also act as voice operated devices to control the attenuation of the networks 8 and 11 and for this purpose they are operated by varying the grid potential in such a way as to vary the mean anode current. It will be evident, however, that entirely separate valves may be used for this purpose if so desired. Such an arrangement is shown in Fig. 3. For the purpose of controlling the amplifier as a voice operated device 7 it is provided with a main input 13 in which are arranged a normally open attenuation network 16 and a rectifier 17, a reply input 14 and a third or anti-echo input 15. The signals applied to the main input 13 are derived from the output side of the amplifier 10. The signals applied to the reply input 14 are derived from the output side of the amplifier 7. The signals applied to the third or anti-echo input 15 are derived from the output side of the amplifier 12.

The amplifier or voice operated device 10 similarly has a main input 18 in which are arranged a normally open attenuation network 21 and a rectifier 22, a reply input 19 and a third or anti-echo input 20. The signals applied to the main input 18 are derived from the output side of the amplifier 7. The signals applied to the reply input 19 are derived from the output side of the amplifier 10. The signals applied to the anti-echo input 20 are derived from the output side of the amplifier 7.

The attenuation of the networks 16 and 21 is also controlled by the voice operated devices 10 and 7. Signals applied to the main input 13 tend to operate the voice operated device 7 so as to close the network 21 and open the network 11 successively. Signals applied to the reply input 75

14 tend to operate the device 7 in the reverse direction so as to close the network 11 and open the network 21 successively. Signals applied to the third or anti-echo input 15 tend to prevent this reverse operation of the device 7 in dependence upon the value of the signals applied to the anti-echo input 15 so that only if the amplitude of the signals applied to the reply input 14 are sufficiently great can they have any effect upon the voice operated device 7. Similarly signals applied to the main input 18 tend to operate the voice operated device 10 so as to close the network 16 and open the network 8 successively. Signals applied to the reply input 19 tend to operate the device 10 in the reverse direction so as to close the network 8 and open the network 16 successively. Signals applied to the third or anti-echo input 20 tend to prevent this reverse operation of the device 10 in dependence upon the value of the signals applied to the third or anti-echo input 20 so that only if the amplitude of the signals applied to the reply input 19 are sufficiently great can they have any effect upon the voice operated device 10.

25 In the quiescent state the networks 8 and 11 are closed. Instability due to electrical coupling of the transformer 4 and acoustic coupling between the loudspeaker 2 and microphone 1 is thus prevented. When speech signals are received from the microphone 1 they are amplified by the amplifiers 6 and 7 and applied to the main input 18 of the voice operated device 10. The device 10 is thereby operated to close the network 16 and open the network 8 successively. The signals can thus pass through the network 8 and transformer 4 to the line 3. Signals from the microphone 1 which may reach the amplifier 10 due to echo effect or due to lack of balance of the transformer 4 and incoming signals from the line 3, are prevented from reaching the loudspeaker 2 by the closed network 11 and are prevented from operating the device 7 by the closed network 16. When speech signals from the microphone 1 cease the voice operated device 10 restores to the quiescent state condition to close the network 8 and open the network 16 successively. There is however a hangover time which must elapse before this restoration takes place, this hangover time being sufficient to bridge the gaps between words. If, now, whilst the apparatus is in the quiescent state, reply signals are received from the line 3 these signals are amplified by the amplifier 10 and applied to the main input 13 of the voice operated device 7. The device is thereby operated to close the network 21 and open the network 11 successively. The reply signals can then pass through the network 11 and amplifier 12 to the loudspeaker 2. Originating and echoing signals applied to the microphone due to the acoustic coupling between the loudspeaker 2 and the microphone 1 are prevented from reaching the line 3 by the closed network 8 and are prevented from operating the device 10 by the closed network 21. When the reply signals cease the voice operated device 7 restores to the quiescent state condition to close the network 11 and open the network 21 successively. A hangover time is also provided in this case to bridge the gaps between words.

70 If during the transmission of speech signals from the microphone 1, reply signals are received from the line 3, these reply signals pass through the amplifier 10 to the reply input 19 and during a falling away in the strength of the speech sig-

nals from the microphone, for instance due to a weak syllable cause reverse operation of the device 10 to close the network 8 and open the network 16. As soon as the network 16 opens the reply signals can pass through the main input 13 and effect operation of the voice operated device 7 to close the network 21 and open the network 11 successively. The reply signals are then able to pass through the network 11 and amplifier 12 to the loudspeaker 2. It will thus be seen that during the transmission of signals from the microphone reply signals may break in and cease to wait for the control time to elapse.

Since echo signals are also applied to the reply input 19, it is necessary to prevent such signals operating the device 10 in a similar manner to the reply signals to effect a break in. This is achieved by means of the signals applied to the third or anti-echo input 20, which signals are derived from the same source as the echo signals. It is arranged that the signals applied to the third or anti-echo input 20 always have a greater effect than the corresponding echo signals applied to the reply input 19. By this means the echo signals are prevented from operating the device 10, whilst reply signals, which have a greater amplitude than the anti-echo signals, are not prevented from operating the device 10. The effect of anti-echo signals applied to the anti-echo input 20 is maintained for a time which is sufficient to guard against the echo signals which pass round the circuit to the reply input 19 but which is considerably less than the hangover time of the device 10.

In a similar manner, during the reception of reply signals from the line 3, signals applied to the microphone 1 may break in by causing a reverse operation of the device 7 through the reply input 14. Echo signals applied to the microphone 1 are prevented from effecting a break in by anti-echo signals applied to the anti-echo input 15.

The parts shown in Fig. 1 are shown in greater detail in Fig. 2 where like parts have like reference numerals. As shown in Fig. 2 the attenuation networks each comprise a plurality of dry plate rectifiers arranged in shunt and series arms. The attenuation of each network is controlled by direct current passing through the rectifiers which thus determines the alternating current impedance of the rectifiers.

Attenuation networks of this kind are described in British specification No. 413,383. It will therefore suffice for the purpose of this description to say that the attenuation of each network is varied by the D. C. control current which passes through the rectifiers in such a direction that the attenuation of the network is varied by varying the value of the control current, and it should be pointed out that under certain critical conditions a slight change in the value of the control current will cause the attenuation to vary within very wide limits. One of the features of the invention concerns the utilization of this property for the purpose of ensuring that the attenuation of the networks is varied in a predetermined order. The microphone is connected to the leads 40, and the loud-speaker to the leads 41. The attenuation network 16 is represented by two networks in series in Fig. 2, the combined networks having a pair of control terminals 23 and 24 to which the D. C. control current is applied. Similarly the attenuation network 21 is represented by two networks in series in Fig. 2 the combined networks

having a pair of control terminals 25 and 26. The network 8 has a pair of control terminals 27 and 28, the network 11 has a pair of control terminals 29 and 30.

5 For convenience in order to enable the supply of the control current to the different networks to be readily followed reference might be had to Fig. 4 as well as Fig. 2, Fig. 4 showing exactly the same arrangement as Fig. 2 but eliminating as far 10 as possible all details so that the networks are only shown as rectangles, and certain equipment which is not necessary for the understanding of the control circuits is eliminated.

The two voice operated devices 7 and 10 each 15 of which consists of a valve, control the attenuation of the networks by means of a bridge arrangement, the valves 7 and 10 forming two complementary arms of the bridge and the resistances 31 and 32 forming the other two complementary 20 arms of the bridge. The high tension battery 33 is connected across one diagonal of the bridge, having its positive pole connected to the junction point of the resistances 31 and 32 and its negative pole or earth connection connected to earth in the filament circuit of the valves, the control circuits of the networks being connected in series across the other diagonal between the points 34 and 35. The path of the control current may be traced from point 34 25 to point 35 through terminals 25, 26, 27, 28, 30, 29, 24, 23, choke 36 to point 35.

The choke 36 serves to reduce alternating current ripple in the control circuit. In the quiescent state the bridge is balanced by adjusting the resistance 32 so that the points 34 and 35 are at 30 the same potential. The attenuation of the networks in the quiescent state is adjusted to the desired values by biassing current applied to the control circuits. For this purpose see Figs. 2 and 40 4. Terminals 26 and 27 are connected to earth through a resistance 37. Terminals 24 and 29 are connected to earth through a resistance 38 and terminals 28 and 30 are connected to the positive pole of battery 33 through a resistance 39. 45 Thus in the quiescent state biassing current flows through the control circuits of the networks 16 and 21 in such a direction that these networks have a low attenuation and may be considered as open. At the same time biassing current flows through the control circuits 8 and 11 in such a direction that the networks have a high attenuation and may be considered as closed.

Variation of the attenuation of the networks is effected by unbalancing the bridge so that the 50 control current flows in one direction or the other between the points 34 and 35. This current might be considered for the purposes of description as being quite separate from the biassing currents, the biassing currents being substantially steady 55 and comparatively small in value compared with the control current which is superimposed on it. If the bridge is unbalanced so that control current flows from the point 34 to the point 35, then in networks 21 and 11 the control current flows 60 in the same direction as the biassing current so that these networks remain opened and closed respectively, but the control current in the networks 8 and 16 flows in opposition to the biassing current and thus closes the network 16 and opens network 8 successively. It is important that the 65 network 16 should be closed before the network 8 opens as otherwise in the case of a transfer from one direction to the other it is possible for speech passing through the attenuation network 70 8 being able to cause, due to echo or out of balance effects, the back action through the network 16, which would interrupt the operation of the amplifier 7 and so create a condition whereby the speech transmitted was intermittently interrupted due to the network 8 being again closed. 5

The presence of the different biassing currents ensures that the changeover takes place in the correct order. Due to the presence of condenser and inductance in the control current bridge circuit the changeover does not take place instantaneously and the fact that the biassing currents of the two networks 8 and 16 are in different relative directions as well as being possibly different in value, ensures that the network 16 is closed in advance of the opening network 8. That is to 15 say the critical condition whereby the change takes place from high or low attenuation or vice versa is first reached in network 16 and is subsequently reached in network 8.

The presence of inductance or condensers in the 20 circuits ensures that the critical condition is reached at different times in the different networks, and also ensures that if the change in the control voltage is of a small nature then the tendency would be for both networks to be closed 25 rather than for them both to be open at the same time, which latter condition interferes as explained above with the proper operation of the system. It will be understood that the control is not limited to a bridge circuit but is applicable 30 to any arrangement in which a number of networks are jointly controlled, that is by the same control voltage or the same control current and the biassing currents or potentials of the different networks vary. 35

If the bridge is unbalanced so that the control current flows from the point 35 to the point 34, then in networks 16 and 8 the control current flows in the same direction as the biassing current so that the networks 16 and 8 remain open 40 and closed respectively, but the control current in the networks 11 and 21 flows in opposition to the biassing current and thus closes the network 21 and opens the network 11 in the order mentioned. The value of the resistance 39 again 45 ensures that the biassing currents are such that the network 11 closes before the network 21 opens. The unbalancing of the bridge so that the control current flows from the point 34 to the point 35 is effected by operation of the voice 50 operated device 10. The device 10 is operated by decreasing the negative grid bias of the valve so as to increase the mean anode current and thereby lower the potential of the point 35 with 55 respect to the point 34. The negative grid bias is decreased by signals applied to the main input 18. These signals pass through the network 21, are rectified by the rectifiers 22 and applied to a pair of condensers 42 so as to charge them in opposition to the grid bias batteries 43. When 60 signals are removed from the main input 18 the charge on the condensers 42 leaks away through the resistance 44 so that the grid bias of the device 10 returns to that which exists in its quiescent state, the value of the resistance 44 65 being so chosen as to give the necessary hang-over time, that is, to ensure that transfer will not take place from one direction to another between syllables.

A similar restoration of the grid bias of the device 10, as already explained, may be effected by signals applied to the reply input 19 without waiting for the hangover time to elapse. These signals are rectified by a rectifier 45 and applied to the condensers 42 so as to discharge them 75

rapidly during a weak syllable of the signals applied to the main input 18, and thereby cause the grid bias of the device 10 to restore to that which exists in its quiescent state. Signals applied to the third or anti-echo input 20 are rectified by a pair of rectifiers 46 and applied to a pair of condensers 47 so as to charge them in opposition to the voltage derived from the input 19, which voltage tends to discharge the condensers 42. The voltage across the condensers 47, due to any signal applied to the anti-echo input 20, is always greater than the maximum voltage of the corresponding echo or other signal derived from the original signal and applied to the reply input 19. By this means the echo or like signal can never be rectified by rectifier 45 to cause a discharge current to flow from condenser 42. The condensers 47 are provided with a discharge resistance 48, chosen so that the hangover time of the condensers 47 is slightly greater than the time taken for the echo signal to reach input 18. When a reply signal is applied to the reply input 19 it will be rectified by the rectifier 45, and so discharge the condensers 42 provided its maximum voltage exceeds the voltage across the condensers 47.

If the echo time is short or practically instantaneous, the hangover time of the condensers 47 need only be a few milli-seconds so that the condensers 47 discharge between syllables. Reply signals are thus not prevented by the condensers 47 from discharging the condensers 42. The unbalancing of the bridge so that the control current flows from point 35 to the point 34 is effected by operation of a voice operated device 7. The manner of operation will be evident from the description given above of the operation of the device 10. Signals applied to the main input 13 are rectified by the rectifiers 17 so as to charge a pair of condensers 49 in opposition to the grid bias batteries 50. Signals applied to the reply input 14 are rectified by the rectifier 51 so as to discharge the condensers 49. Signals applied to the anti-echo input 15 are rectified by a pair of rectifiers 52 so as to charge a pair of condensers 53 in such a direction as to prevent the discharge of the condensers 49 by echo signals applied to the reply input 14.

The application of the invention to a two-wire repeater circuit is shown schematically in Fig. 3; circuit details are not shown as these will be evident to those versed in the art from the description of the previous circuits. Parts corresponding to those in the previous circuits have like reference numerals. As shown, the line 3 is coupled to the "go" and "return" paths through the hybrid coil or differential transformer 4. The "go" path comprises an equalized four-wire repeater 53, normally closed attenuation network 8 and a transmission amplifier 54. The "return" path comprises an equalized four-wire repeater 55, a normally closed attenuation network 11 and a transmission amplifier 56. The attenuation of the networks is controlled in a similar manner to that of the circuits already described. The method of operation will therefore be clear from this previous description. In this case however the voice operated devices 7 and 10 while they may amplify, do not serve the additional purpose of transmission amplifiers; the signal transmission paths and the control paths are entirely separate.

It will be noted that the voice operated devices 7 and 10 each have three input circuits as be-

fore and these serve exactly the same purpose. The inputs can be described as follows, namely, the main inputs 13 and 18, the reply inputs 14 and 19 and the third or anti-echo inputs 15 and 20.

It will be understood that the invention is not specifically limited to the particular arrangements described as several modifications can be made in the circuit details without departing from the spirit of the invention. For instance the invention is not limited to two-way transmission circuits as it can be readily applied to other transmission circuits, for example two one-way circuits which should not overlap, while the arrangement for controlling attenuation networks in a definite order is capable of application in any circuits where the properties referred to might be used to advantage.

I claim:

1. In an alternating current signalling system having two transmission paths for signals of voice frequency, the combination comprising an attenuating device arranged in one of said transmission paths, said device serving to control the attenuation of said path, and a voice operated device associated with said attenuating device and having a main input connected to the input side of one of said transmission paths, a first auxiliary input connected to the input side of the second of said transmission paths, and a second auxiliary input connected to the input side of the first of said transmission paths, signals applied to said main input serving to operate said voice operated device in one direction to change the attenuation of said attenuating device, the signals applied to said first auxiliary input serving to operate the device in the reverse direction to reverse said change of attenuation, and the signals applied to said second auxiliary input, provided that they are sufficiently strong, serving to prevent said reverse operation of the voice operated device.

2. In an alternating current signalling system having two transmission paths for signals of voice frequency, the combination comprising a voice operated device, said voice operated device serving to control the attenuation of at least one of said transmission paths to prevent echo effects, means for operating said device to change the attenuation of said one transmission path, said means being responsive to signals in one of the said transmission paths, and first auxiliary means for operating said device to reverse said change of attenuation, said first auxiliary means being responsive to signals in the input side of the second of said transmission paths during transmission in the first path, and second auxiliary means for suddenly rendering said first auxiliary means effective, said second auxiliary means being responsive to signals in said first transmission path.

3. In an alternating current signalling system having two transmission paths for speech signals and in which echo signals derived from signals in one of said paths are liable to produce an effect resembling that produced by signals in the other of said paths, the combination of change-over means for permitting signal transmission to change from one of said paths to the other, delay means for preventing said change-over means operating during the interval which usually exists between words, preventive means for preventing said echo signals producing said effect, and further delay means for ensuring that said preventive means are only effective for a

time which is less than said interval between words and slightly longer than the time taken for said echo signals to produce said effect.

4. In an alternating current signalling system having two transmission paths for speech signals, the combination comprising an attenuation device arranged in one of said transmission paths, said device serving to control the attenuation of said path, a condenser associated with said attenuation device, the attenuation of said device being dependent on the condenser voltage, a rectifier interposed between the input to one of said transmission paths and the condenser, said rectifier serving to charge the condenser with rectified signal current, a high resistance discharge path for said condenser, a second rectifier interposed between the input side of the second transmission path and the condenser, said second rectifier serving to apply signals from said second path to discharge said condenser rapidly, and a source of biasing voltage applied to said second rectifier and derived from the input to the first transmission path, said biasing voltage being dependent on the strength of the signals in the input to the first transmission path and serving to prevent the rectifier applying signals to discharge said condenser so long as these signals are not sufficient to overcome said bias so that the condenser is not discharged by echo signals.

5. The combination claimed in claim 4, wherein in the said source of bias voltage comprises a second condenser, a third rectifier interposed between the input to the first transmission path and said second condenser, said third rectifier serving to charge the second condenser with rectified signal current, and a discharge path for said second condenser, the resistance of the discharge path of said second condenser being sufficient to maintain the effect of a signal for a time which is just sufficient for the echo of that signal to reach said second rectifier.

6. The combination claimed in claim 4, wherein in an amplifier is interposed between the input side of the second transmission path and said second rectifier.

7. In an alternating current signalling system having a plurality of signal paths, the combination comprising at least two attenuation networks arranged in the signal paths, the attenuation of each of said networks being controlled by an applied control voltage, the attenuation vary-

ing considerably when the applied control voltage passes through a critical value, a source of control voltage arranged to be applied to control points in said networks, said voltage jointly controlling the networks, means for varying said control voltage, at least one source of biasing voltage applied to said networks, means for differently biasing the networks of the respective paths so that when the applied control voltage is varied the critical changes in the attenuation in the different networks of a signal path take place consecutively.

8. In a two-way telephone system having two transmission paths, the combination comprising a normally closed attenuation network arranged in one of said transmission paths, attenuation control apparatus, said apparatus having one input associated with the input side of the one transmission path and a second input associated with the input side of the other transmission path, a second normally open attenuation network arranged in said second input, said control apparatus applying a control voltage to the two networks to control the attenuation thereof jointly, signals applied to the first input tending to open the first network and close the second network and signals applied to the second input tending to close the first network and open the second network, and a source of bias voltage applied to at least one of said networks, said bias ensuring that the second network closes slightly in advance of the opening of the first network to prevent application of signals to the second input to close the first network.

9. In an alternating current signalling system having a plurality of signal paths, the combination comprising at least two attenuation networks arranged in the signal paths, each of said networks having a control circuit the voltage applied to which controls the attenuation of the network, a bridge circuit, the control circuits of said networks being connected in series in a diagonal circuit extending between a pair of opposite corners of the bridge, at least one connection between an intermediate point of said diagonal circuit and the potential of some point of the bridge, said connection serving to bias said networks differently, and means for unbalancing said bridge circuit in response to signals in at least one of the signal paths.

LEONARD ERNEST RYALL.
